UNITED STATES PATENT OFFICE.

EDWARD C. FOWLER, OF FORESTVILLE, CONNECTICUT, ASSIGNOR OF THREE-FOURTHS TO GEORGE A. DOWNS, OF SAME PLACE, AND WILLIAM E. SIMONDS, OF CANTON, CONNECTICUT.

NAIL-PULLER.

SPECIFICATION forming part of Letters Patent No. 588,744, dated August 24, 1897.

Application filed December 14, 1896. Serial No. 615,710. (No model.)

To all whom it may concern:

Be it known that I, EDWARD C. FOWLER, a citizen of the United States of America, residing at Forestville, in the county of Hartford and State of Connecticut, have invented a certain new and useful Improvement in Nail-Pullers, of which the following is a description, reference being had to the accompanying drawings, wherein—

10 Figure 1 is a full-length view of the complete device. Fig. 2 is an end view—a view of the end carrying the bit. Fig. 3 is a full-length view of a sectional part of the device comprising a single nail-notch. Fig. 4 is a view 15 of the part shown in Fig. 3, turned a quarter-way around.

In the accompanying drawings, the letter *a* denotes the handle. Its upper end is shaped, formed, and adapted to receive and sustain 20 longitudinally-directed blows, and its sides in whole or in part approximate the flat rather than the cylindrical in form, to the end that they may thereby be adapted to receive and sustain laterally-directed blows.

25 The letter *b* denotes an edged part or bit attached to the handle. When shaped as shown in Figs. 1 and 2, it is annular in form.

Each letter *c* denotes a nail-notch, by which is meant a notch formed in the bit and adapted 30 to straddle a nail in the act of pulling it. Each nail-notch is in the same general alinement with an aforesaid flattened space upon the side of the handle.

On looking at the bit, as shown in Fig. 2, it 35 will be seen that the parts or sections of the edge which are next a notch and upon either side thereof and lying in a plane at substantially right angles to the axis of the shaft converge to the notch on lines which are parts of 40 a circle, the center of which circle substantially coincides with the axis of the handle.

An annular bit affords space and place for nail-notches of different sizes, all in a similar relation to the handle. The annular part of

the device has an opening or openings rearward of the nail-notches adapted to afford a view of the contact of a nail-notch with a nail in the act of nail-pulling. 45

In the use of the device the operator holds it in one hand and a hammer in the other. 50 He places the bit in slanting contact with the wood in such position as to eventually bring a nail-notch astride the body of the nail to be pulled. Then by driving upon the end of the handle the bit is made to enter the wood 55 so as to underlie the head of the nail. Then by striking downward on the side of the handle he pries the nail outward from its seat in the wood.

I claim as my invention—

1. The handle formed and adapted to there receive and sustain longitudinally-directed driving-blows and also having a flattened side and thereby adapted to there receive and sustain laterally-directed prying-blows, in combination with a bit containing a nail-notch located in general alinement with said flattened side of the handle and having on either side of the notch sections of the edge located in a plane substantially at right angles to the axis of the handle and converging to the notch on lines which are parts of a circle the center of which circle substantially coincides with the axis of the handle, all substantially as described and for the purposes set forth. 65

2. The combination of the handle with the annular bit having nail-notches formed therein and also having an opening rearward of the nail-notches adapted to afford a view through such opening of the contact of a nail-notch with a nail, in the act of nail-pulling, all substantially as described and for the purposes set forth. 70

EDWARD C. FOWLER.
